(57) **CLAIM**

The ornamental design for a tool implement release collar, as shown and described.

DESCRIPTION

FIG. 1 is an isometric view of a tool implement release collar showing our new design;

FIG. 2 is an isometric view thereof;

FIG. 3 is a front elevation view thereof;

FIG. 4 is a rear elevation view thereof; and,

FIG. 5 is a top plan view thereof, the bottom plan view, the right side elevation view and the left side elevation view each being a mirror image thereof.

The broken lines shown in FIGS. 1 and 4 represent portions of the tool implement release collar that form no part of the claimed design.

1 Claim, 5 Drawing Sheets
